ELECTRIC LOCOMOTIVE

Léon Heidmann, Jeumont, France, assignor to
 Forges et Ateliers de Constructions Électriques
 de Jeumont, Paris, France, a French body cor-
 porate

Application July 14, 1947, Serial No. 760,881
 In France August 1, 1946

11 Claims. (Cl. 105—49)

1

This invention relates to electric locomotives, in which the satisfactory lay-out of the equipment involves numerous very varied and often contradictory problems; for example, regard must be had to the accessibility of its various parts, the facility of dismantling, replacement and cleaning, the reduction and simplification of the wiring, the efficiency and economy of the cooling and ventilation system, the safety of the crew, so on.

The main object of the present invention is to provide a solution of all these problems at once, which is very difficult in practice, by a general arrangement or lay-out which enables this to be done by simple means and in a very thorough manner.

According to my invention, in an electric locomotive of the type having the whole equipment of all traction and auxiliary circuits between the overhead bows or pantographs and the motor terminals, and in particular a certain number of groups of cam contactors, auxiliary contactors, relays, interlocks, reversers, resistances, and the like, as well as a high tension cell, enclosed in a closed chest or cabinet, provided with a suitable number of inspection doors, and arranged in the middle of the locomotive body with complete accessibility on all sides, the traction unit so constituted is provided with a set of fans which are fed by the traction current on the grounded side, and which form part of the starting circuit. The traction unit is arranged to be withdrawable upwardly all in one block, or partially, after separation of its external connections which are readily accessible; it is disposed so that all its internal parts shall be not only wholly accessible from the gangways which surround it, but also easily detachable, and so that its heavy parts, placed preferably towards the base, shall be easily withdrawable in the horizontal direction.

Other objects and advantages of the invention will be better understood upon reference to the following description, relative to an example of construction represented in the accompanying diagrammatic drawing. In this drawing, Fig. 1 is a sectional elevation of the locomotive, Fig. 2 is a plan view, Fig. 3 is a transverse section of the body on the plane *a—a* of Fig. 2, Fig. 4 is a similar section showing a modification, and Fig. 5 is a simplified connection diagram showing the connections of the motors operating the ventilating fans.

In Figs. 1 to 3, there is seen the "traction unit" 1 which will be described later in greater detail, the fans 2 provided for cooling the traction motors 8, the compressors 3, the air reservoirs 4,

2

the battery cabinets 5, the drivers' stands 6 and the cable conduits 7.

The unit 1, which takes the form of a rectangular chest provided with several doors 29, contains a high-tension compartment 9, arranged directly under the roof insulators 10 connected to the pantographs 11; this cell or compartment contains the whole current supply apparatus, including the quick-action main breaker 12. The remainder of the unit 1 which lies to the left of the transverse partition 13 (see Fig. 2) comprises two lateral unventilated cabinets (see Figs. 2 and 3) housing a group 14 of cam-operated rheostat contactors, as well as their operating motor 15, a group 16 of cam-operated coupling contactors with their operating motor 17 and a group 18 of shunting contactors with their operating motor 19.

The operating motors 15, 17 and 19 are mounted externally of the chest for the unit 1, thus enabling the manual operation of the corresponding cam shafts, if necessary.

The motors 15, 17 and 19 have not been shown in Fig. 1 in order to simplify the drawing. The above-mentioned manual operation of the group 14 of rheostatic contactors, normally driven by the motor 15, can be effected by any conventional means, such as for instance a manually-operated shaft 32 extending to the two drivers' stands, and driving the motor 15 by suitable mechanism such as a chain transmission 31.

The traction unit contains likewise various auxiliary contactors and relays 20, the reverser 21 and the resistances 22 connected to their contactors by direct and very short leads 23. The resistances 22 are preferably arranged at the bottom of a central compartment or ventilation channel which starts from the air-inlet grating 24 at the bottom and opens out directly beneath the cowling 25, which can be closed by the shutters 26. Several helicoidal fans 27 driven by individual motors F with vertical shafts ensure the forced air-cooling of the resistances, which arrangement allows of dissipating by an extremely small weight of resistances a sufficient power for ensuring the start of the locomotive; this power can even be carried permanently, if it be necessary. As shown in Fig. 5, the motors F for these fans are preferably mounted directly in series with a traction motor M (being one of the traction motors 8) on its grounded side and in parallel with a resistance R (being one of the starting resistances 22); they are short-circuited at the last notch of the resistance starting operation by a contactor C which forms part of the cam-oper-

ated group 14 controlling the starting resistances 22. This contactor, which is the last to close during the starting of the traction motors, is shown in Fig. 5; it is connected in parallel with the group of fan-motors F described above. By its closure, at the end of the starting operation, the fan-motors F and the resistance R are cut out, and the traction motor M is directly connected to ground.

Operating at very low voltage, these motors F can be insulated for that low voltage to ground and of extremely robust construction. In case of damage to one of them, such damage being notified by a suitable signal or tell-tale device, an individual cut-out switch S allows of isolating it, and the service can continue with the others.

Each fan motor F is cooled by a supply of fresh air, taken in at the second sky-light 28 and drawn along by the fan itself the air passing down a duct within the ventilation channel and escaping through holes in the fan nose, as shown by the arrows in broken lines (in Fig. 3), while the air cooling the resistances circulates upwards past the fan and is driven along the ventilation channel outside the duct therein to escape beneath the cowling 25 as shown by the arrows in full lines. Accessibility to the commutators of these motors F is provided from the side gangways of the locomotive, inspection doors for this purpose being shown by the arrow F'; dismantling of the fans is effected by way of the cowling or sky-light 28.

It is to be noted that the energy for driving the fans is taken from the energy usually wasted in the starting resistances. Moreover, the feeding of the fans by the traction current itself according to Fig. 5 ensures in a particularly simple manner and without a special installation or a protective device, an automatic and reliable cooling of the rheostats 22. Lastly, due to this mode of operation, the intensity of the cooling action increases automatically with the starting current, and therefore with the power to be dissipated.

The traction unit 1 is located between two wide lateral gangways from which it is separated by several doors 29 which allow of inspecting all the internal equipment, including the resistances. These latter are mounted preferably upon insulating supports of fusiform section, described in the French patent application filed on June 24, 1946, for "Easily Cleaned Supporting Insulators."

Each resistance box can be withdrawn horizontally after dismantling the few connectors which lead thereto.

The unit 1 which contains all the electrical gear relating to the traction and to its auxiliary circuits, can be withdrawn upwards in a single piece after simply unwiring the connectors leading to the pantographs and to ground, the cables leading to the motors and the high-tension auxiliaries, and after the separation of a few couplings for the auxiliary circuits; if desired, the resistances can remain in place.

After this withdrawal as a single block, the traction unit can be broken up into several parts which can be forwarded to the various repair or maintenance shops; it is possible, for example, to subdivide it into three parts comprising respectively the fans, the resistances and the remainder which constitutes the traction equipment proper.

The example represented in Figs. 1 to 3, relating to the very unfavourable case of a locomotive of short wheel-base, shows that access to all the apparatus is freely provided. In the case of a

locomotive of greater length, the end boxes 5 can with advantage be placed at the end of the traction unit 1, in front of the fan and compressor groups 2 and 3. In the case of a locomotive having six axles, the ventilation of the two central traction motors can be furnished for example by two helicoidal fans with vertical shafts, enclosed in the unit 1 in the manner of the fans 21, which allows again of installing the unit 1 in the very center of the locomotive.

The arrangement described presents in addition the following advantage:

In the case of damage to the operating means for the cam contactors, their shafts, which are readily accessible, can be operated by hand from any one of the drivers' stands, which allows of effecting notch-by-notch various starting operations.

It is to be noted moreover that the lay-out described allows of placing the parts such as the contactors, relays, controllers, etc., at the most suitable height for their inspection and examination; that the length of all the connectors and cables is reduced to the minimum, and that, in particular, the relative disposition of the contactors and resistances allows the use of straight and practically parallel connectors 23, shown in Fig. 3 in the form of tubes or bars, which may be left bare, fixed on the front side of the equipment behind the inspection doors 29 (Fig. 1). It will be seen also that effective ventilation is obtained by simple means and in a very economical way, and that all the other conditions mentioned in the introduction to this specification are realized completely.

The advantages of the arrangement described above are more especially appreciable when all the elements of the apparatus, for example the contactors, relays, resistances, etc. are made to be detachable and replaceable very quickly and without special tools.

As a modification, the fans 21 for the resistances can blow downwards fresh air drawn in through the cowling or sky-light, and in this case the special air inlet 28 for the cooling of the fan motors can evidently be suppressed.

As a further modification, the overhead cowling is suppressed and the cooling air is drawn into the locomotive body through suitably provided louvers 30 at the sides, the air passing over the lateral cabinets enclosing the groups 14, 16 and 18, and escaping through the outlet grating under the ventilated compartment, as shown in the diagram of Fig. 4.

What I claim is:

1. In an electric locomotive of the type having a plurality of traction motors, a central chest provided with doors, two lateral unventilated cabinets for traction control apparatus and a ventilated compartment for air-cooled resistances, means for improving the general lay-out, increasing the efficiency of the cooling system and controlling automatically the forced air-flow through said compartment, comprising an upright ventilation channel located between said lateral cabinets and containing a plurality of individually driven fans, motors for driving said fans being connected in parallel and inserted into a ground connection of said traction motors whereby said fan-driving motors are controlled by the main current of the traction motors at starting the locomotive.

2. In an electric locomotive according to claim 1, means for controlling economically without auxiliary apparatus the forced air-flow produced

by said fans, comprising the connection of said fan-motors between said traction motors and ground, said fan-motors carrying the main starting current of at least one of said traction motors, whereby said fan-motors are automatically controlled at a very low voltage to ground, and being accordingly insulated for such very low voltage.

3. In an electric locomotive according to claim 1, means for automatically controlling the forced air-flow produced by said fans, according to which said fan-motors are connected in parallel to form a group inserted between at least one of said traction motors and ground in order to carry the starting current of the locomotive, a contactor provided for the last starting notch being connected across said group, whereby the fan motors are equivalent to a last section of starting resistance for said traction motor.

4. In an electric locomotive according to claim 1, means for automatically and economically controlling without auxiliary apparatus the forced air-flow produced by said fans, characterized by the fact that all said fan-motors are connected in parallel with a resistance to form a low-voltage group which is inserted into the ground connection of one of said traction motors to carry the starting current of the locomotive, and a starting contactor provided for producing the last starting notch is connected for short-circuiting said low-voltage group.

5. In an electric locomotive of the type having a plurality of traction motors, a central chest provided with doors, two lateral unventilated cabinets for traction control apparatus and a ventilated compartment for air-cooled resistances, means for improving the general lay-out, increasing the efficiency of the cooling system and controlling automatically the forced air-flow through said compartment, comprising an upright ventilation channel located between said lateral cabinets and containing a plurality of individually driven fans, motors for driving said fans being inserted into a ground connection of said traction motors, an air-inlet grating under said ventilated compartment, an air-outlet cowling at the upper end of said ventilation channel, and shutters in said cowling.

6. In an electric locomotive of the type having a plurality of traction motors, a central chest provided with doors, two lateral unventilated cabinets for traction control apparatus and a ventilated compartment for air-cooled resistances, means for improving the general lay-out, increasing the efficiency of the cooling system and controlling automatically the forced air-flow through said compartment, comprising an upright ventilation channel located between said lateral cabinets, said channel having a less height than the roof of the locomotive and containing a plurality of individually driven fans, motors for driving said fans being inserted into a ground connection of said traction motors, lateral air-inlet louvers in the body of the locomotive, and an air-outlet grating under said ventilated compartment.

7. In an electric locomotive of the type having a plurality of traction motors, a central chest provided with doors, two lateral unventilated cabinets for traction control apparatus and a ventilated compartment for air-cooled resistances, means for improving the general lay-out, increasing the efficiency of the cooling system and controlling automatically the forced air-flow through said compartment, comprising an upright ventilation channel located between said lateral cab-

inlets and containing a plurality of individually driven fans, motors for driving said fans being inserted into a ground connection of said traction motors, a starting controller in one of said lateral cabinets, an auxiliary control motor mounted outside of said chest for operating said controller, and mechanism for manual operation of said control motor.

8. In an electric locomotive of the type having a plurality of traction motors, a central chest provided with doors, two lateral unventilated cabinets for traction control apparatus and a ventilated compartment for air-cooled resistances, means for improving the general lay-out, increasing the efficiency of the cooling system and controlling automatically the forced air-flow through said compartment, comprising an upright ventilation channel located between said lateral cabinets and containing a plurality of individually driven fans, the motors for driving said fans being inserted into a ground connection of said traction motors, and means for cooling said fan-motors, said cooling means comprising an air-inlet upon the roof of the locomotive and air-conduits interposed between said air-inlet and said fan-motors in order to supply them with fresh air.

9. In an electric locomotive of the type having a plurality of traction motors, a central chest provided with doors, two lateral unventilated cabinets for traction control apparatus and a ventilated compartment for air-cooled resistances, means for improving the general lay-out, increasing the efficiency of the cooling system and controlling automatically the forced air-flow through said compartment, comprising an upright ventilation channel located between said lateral cabinets and containing a plurality of individually driven fans, motors for driving said fans being inserted into a ground connection of said traction motors, the traction control elements enclosed in said chest being arranged and superposed in such order that they are all interconnected by short detachable leads having the form of practically parallel conductors fixed on the front of the equipment behind said doors in easily accessible positions with said doors opened.

10. In an electric locomotive of the type having traction motor control resistances, fans for cooling said resistances, groups of cam-operated contactors cooperating with said resistances, auxiliary control motors for operating separately said groups of contactors, and a central chest enclosing said resistances, fans and contactors, an arrangement and lay-out of said central chest comprising in the upper part of said chest two non-ventilated lateral cabinets for said groups of contactors, between said cabinets an intermediate space for said fans, and interconnected with said intermediate space a ventilated compartment in the lowest part of said chest for said resistances, said auxiliary control motors being located outside of said chest and rotatable by hand for emergency operation of said groups of contactors.

11. In an electric locomotive of the type having a central chest for the electrical traction equipment comprising motor control resistances, fans for cooling said resistances, groups of cam-operated contactors co-operating with said resistances, and individual auxiliary control motors for operating said groups of contactors, an arrangement of said chest according to which all said traction equipment with the exception

of said auxiliary control motors is housed inside of said chest, which comprises in its upper part two unventilated lateral cabinets for said groups of contactors, a space for said fans intermediate between said cabinets, and interconnected with said intermediate space a ventilated compartment in the lowest part of said chest for said resistances, said auxiliary control motors being located outside of said central chest and rotatable manually for emergency hand control of said groups of contactors.
